[57] CLAIM

The ornamental design for a vehicle body, as shown and described.

DESCRIPTION

FIG. 1 is a front, side perspective view of a vehicle body;

FIG. 2 is a rear, side perspective view;

FIG. 3 is a side elevational view, the opposite side is a mirror image;

FIG. 4 is a front perspective view; and,

FIG. 5 is a rear perspective view.

The broken line showing of tires and wheels in all views is for illustrative purposes only and forms no part of the claimed design.
